UNITED STATES PATENT OFFICE.

GUNVALD AUS, OF BROOKLYN, NEW YORK.

CONSTRUCTION OF REINFORCING-STEEL FOR REINFORCED CONCRETE BEAMS AND GIRDERS.

No. 857,973.

Specification of Letters Patent.

Patented June 25, 1907.

Application filed November 27, 1906. Serial No. 345,839.

To all whom it may concern:

Be it known that I, GUNVALD AUS, a citizen of the United States, residing at No. 186 Brooklyn avenue, Brooklyn, in the county of 5 Kings and State of New York, have invented new and useful Improvements in the Construction of Reinforcing-Steel for Reinforced Concrete Beams and Girders.

The invention relates to the connection of the main tension bars and the stirrups or diagonals; and its object is to connect them in a cheap and efficient manner and more especially to provide a system whereby such connections can be made at a shop where the sizes can be readily inspected, so that the assembled pieces can be shipped to the building as a unit ready to be deposited in place.

The invention also provides means whereby the reinforcing steel is kept at the proper distance above the bottom of the mold to insure the desired amount of concrete covering.

Figure 1 shows the completed reinforcing steel ready to be set in place. Fig. 2 is a side elevation showing a reinforced center. Fig. 3 is a detail view showing two die members utilized for indenting the corners of a tension bar. Fig. 4 shows a stirrup or diagonal in isometric projection, and Fig. 5 shows the same stirrup or diagonal in place on the main tension bars. Fig. 6 shows the proposed method of forcing the stirrups or diagonals in place on the main tension bars. Fig. 7 shows a section through the tension bars with a stirrup or diagonal in place. Fig. 8 is a side view of a tension bar showing the depression or dents along the edges. Fig. 9 is a cross-section through a dent or depression. Fig. 10 shows a spacer in place on the main tension bars.

Ordinary square bars are passed between the jaws "A" of a hydraulic press or similar machine and the dents or depression "D" formed along the edges as shown in Figs. 7, 8 and 9. Lighter square bars are bent by any suitable method into stirrups of the shape shown by Fig. 4. The opening "C" being made to suit the different size bars to be used, and only large enough to slip the stirrups on to the bars with a space between the bars of 1" to 1½" or sufficient to allow the concrete to pass through. Between the stirrups

at suitable intervals will be placed the spacers "E" shown in Fig. 10. These spacers will be made of light flat iron, say $\frac{1}{2}'' \times \frac{1}{4}''$ and bent as shown. Their object is to keep the 55 main tension bars the proper distance above the bottom of the finished concrete beams. The required number of stirrups and spacers are slipped on a pair of tension bars and placed at the dents or depression. The bars 60 in pairs and stirrups so assembled are passed under a hydraulic press as shown in Fig. 6 where the stirrups are pressed into the shape shown in dotted outline in Fig. 6, and as shown in the isometric projection in Fig. 5, 65 firmly gripping the main tension bars by being forced into the dents or depressions along the edges of the bars. The main tension bars and the stirrups or diagonals are thus firmly united and the stirrups bear 70 against the shoulders of the dents or depression in the tension bars so that the concrete of the beam gets a positive grip on the tension bars and does not depend only on adhesion to transmit the stresses into the bars. 75

The stirrups may either remain as shown in full lines in Figs. 1 and 2 in a perpendicular position, or, if desired, they may be bent to form diagonals as shown in dotted outline. Any of the corrugated or deformed bars now 80 used for reinforced concrete construction can be used in connection with these stirrups. It is also possible to use plain square or round bars without any dents or depression, but in this case, the positive grip of the concrete is lost and only the advantage of assembling the main tension bars and the stirrups 85 remain. But as the adhesion of cement to steel is generally sufficient to take care of the horizontal shearing stresses, this method 90 may be used to advantage for long spans and light loads. The stirrups may also be used in the form in which they are shown in Fig. 4 without being forced into the tension bars. While this would not be as effective, it would 95 still be an improvement on the stirrups, as used to-day, this being generally a U shaped rod passed under the tension bars.

What I claim as my invention is:

1. A reinforcing means for concrete beams, 100 comprising a plurality of tension bars, and stirrups coiled about the same and inden-

tured between the bars to clamp and space the latter the proper distance apart, thus forming a unit, as set forth.

2. A reinforcing means for composition material, consisting of tension bars having indentures formed in the circumference thereof, stirrups each formed into an angular coil, the strands thereof seated in said indentures

and having parallel arms projecting therefrom with angular ends, portions of the coils ¹⁰ of the stirrups being indentured to hold the tension bars spaced apart, as set forth.

GUNVALD AUS.
